UNITED STATES PATENT OFFICE.

RAYMOND W. CAHOONE, OF PHILADELPHIA, PENNSYLVANIA, ASSIGNOR TO
CHARLES E. CAHOONE, OF NEWARK, NEW JERSEY.

HARNESS-SADDLE.

SPECIFICATION forming part of Letters Patent No. 331,681, dated December 1, 1885.

Application filed February 4, 1881. Serial No. 154,863. (No model.)

To all whom it may concern:

Be it known that I, RAYMOND W. CAHOONE, a citizen of the United States, residing at Philadelphia, county of Philadelphia, in the State of Pennsylvania, have invented certain new and useful Improvements in Harness-Saddles; and I do hereby declare the following to be a full, clear, and exact description of the invention, such as will enable others skilled in the art to 5 which it appertains to make and use the same, reference being had to the accompanying drawings, and to letters of reference marked thereon, which form a part of this specification.

The object of this invention is to reduce the 15 cost and facilitate the process of manufacturing saddles; and it consists in the peculiar arrangements and combinations of parts, substantially as will be hereinafter set forth, and finally embodied in the claim.

Referring to the accompanying drawings, in which like letters of reference indicate corresponding parts in each of the figures, Figure 1 is a vertical section of a portion of a harness-saddle, showing the relation of an adjustable or separable back-band loop to the other parts of said saddle. Fig. 2 is a plan of a portion of the under plate of said saddle. Fig. 3 is a plan of a holding-plate and the loop in connection therewith. Fig. 4 is a plan of 25 the bottom of a portion of the same, and Fig. 5 is a detached view of the loop.

In said drawings, *a* indicates the usual leather flap, having the terret-perforation *b* and hook-perforation *c*. *d* is a holding-plate 30 which passes up under the jockey to the terret, and is thereby held in position, the terret passing through the opening *e* in said holding-plate. Said holding-plate is provided at the

lower end thereof with a hook or other fastening, *f*, which passes down through the flap 40 and enters into holding engagement with the under plate, *g*. Back of said hook the said plate *d* is provided on the under side with a loop-holding lug, *h*, which extends down to 45 said flap and provides a bearing for the perforated shank *k* of the separable back-band loop *m*. The said shank *k* is held up from the flap and against the plate *d* by a suitable lug, *n*, and thus any danger of the shank slipping 50 under the holding-lug is obviated.

The sides *o o* of the holding-plate are turned 55 down to provide side bearings, which prevent the shank of the loop from moving laterally to any objectionable degree. By this construction the loop may be finished apart from the part *d*, so that should one portion be in gold 60 and the other finished in black the same can be accomplished at a greatly-diminished expense as compared with the cost of doing the same where the parts are integral.

Having thus described the invention, what I claim as new is—

In combination, in a saddle, the flap and perforated under plate, the holding-plate having the hook *f*, lug *h*, and bearings *o o*, and the 65 separable loop *m*, having the perforated shank and lug *n*, all said parts being arranged and operating substantially as and for the purposes set forth.

In testimony that I claim the foregoing I 70 have hereunto set my hand this 2d day of February, 1885.

RAYMOND W. CAHOONE.

Witnesses:

CHARLES H. PELL,
OSCAR A. MICHEL.
